UNITED STATES PATENT OFFICE.

BENJAMIN M. STEELE, OF PEORIA, ILLINOIS.

FRONT-FACING AUTOMATIC FEATHERING-OAR.

SPECIFICATION forming part of Letters Patent No. 358,757, dated March 1, 1887.

Application filed April 26, 1886. Serial No. 200,159. (No model.)

To all whom it may concern:

Be it known that I, BENJAMIN M. STEELE, of Peoria, in the county of Peoria, State of Illinois, have invented an Improved Front-Facing Automatic Feathering-Oar; and I do hereby declare that the following is a full, clear, and exact description thereof.

The object of this invention is the construction of an improved front-facing self-feathering oar.

My front-facing oar is of the kind in which the oar is made in two pivoted portions provided with intermeshing gears, whereby the rearward swing of the handle portion is made to force backward the oar and send the boat in the same direction in which the oarsman is facing. To simplify and render more durable this form of front-facing oar, I have devised the following construction, reference being had to the accompanying drawings, in which—

Figure 1 is a plan view of the oar mechanism; Fig. 2, a central horizontal section of the same; Fig. 3, a perspective view of the entire oar.

The paddle portion O of the oar and the handle O' are each pivoted between the two plates A, and provided with the intermeshing gears F. Said plates are rigidly connected by the posts A', and from the lower plate extend the bearing-arms B, terminating in the bearing-pins B', which are adapted to enter the eyes C' of the bearing-posts C, inserted into the gunwales of the boat. Said bearing-posts have shoulders C² to hold them at the right height above the gunwale, and are perforated at their lower ends for the insertion of split pins C³ to prevent their withdrawal. Formed as a part of each gear F is a socket, into which are inserted the inner ends of the parts of the oar. The handle O' is made fast in the socket E' by means of a rivet or bolt, E²; but the paddle portion O is held loosely in the socket E of the other gear. Through the upper side of said socket E is the slot S, extending about ninety degrees of the circumference of the socket. The pin P, projecting through said slot from the oar-stem in the socket, retains the oar in place and limits the rocking thereof to approximately a right angle.

Pivoted to the top plate, A, are the shifting-levers L, coupled together by the link M, and

the object of which is to alternately engage with the pin P and rock the oar in the way termed "feathering."

The elongated button N is held at one end 55 to the plate A by means of the gear-pivot F' and at its other end to the socket E' by a suitable pin, N', so that the said button oscillates with the oar-handle. The same result is accomplished by casting said button as a part of 6c the socket E', or otherwise rigidly connecting it thereto so as to project in toward the center of the plate A. The object of said button is, by its impress with the end L² of either lever 65 at the end of the oar's swing in one direction, to shift the said levers, and by their engagement with the pin P to rock the oar O.

As shown in Fig. 1, by pulling the handle O' the oar O swings backward in the same direction until the pin P comes in contact with 70 the nearer lever L. The button N at the same time meets the end L² of said lever, and swings it and the pin P so that said pin is moved to the opposite end of the slot S, thereby rocking the oar-blade from its vertical and working position to its approximately horizontal and feathering position. In the same way the oar is, at the opposite termination of its stroke, rocked from its feathering position to its working one, the two levers L being united by the 75 link M, in order that the working movement of one shall give to the other the proper replacing to adapt the same for engaging with the pin P. A tension-spring substituted for the link M would serve the same purpose; but the 80 way shown I deem more preferable.

To lock the oar-blade O in the feathering and working positions, I secure to the socket E, at the side of the slot S, the spring R, having the locking-notches R'. When the oar is 90 caused to rock and bring the pin P to either end of the slot S, said pin fits in the notch R' thereof, and the pressure of the spring holds the same therein. Said spring is made sufficiently strong to hold the oar from turning 95 either when feathering or working, but not so strong but that the oar can shift when the pin P is met by the shifting-levers L.

As shown in Fig. 3, one or both the bearing-posts C have their eyes C' offset to bring the 100 bearing center of the oar nearer the edge of the boat's gunwale, and thereby enable the

oar to be folded together and its blade dropped within the gunwale.

I am aware that prior to my invention front-facing oars have been constructed in which 5 intermeshing gears were employed for giving the desired opposite oscillation to the handle and blade; but my construction thereof is a great improvement.

What I claim as my invention, and for which 10 I desire Letters Patent, is as follows, to wit:

1. In a feathering-oar, the combination, with the plate, of the slotted socket pivoted thereto, the oar-blade having its stem loosely mounted in said socket, the pin projecting from said 15 stem through said slot, a button held by said plate, and the levers pivoted to said plate and adapted by their engagement with said button and pin to oscillate the oar-blade and give it the desired feathering motion.

20 2. The combination, in a feathering-oar, of the plate, the slotted socket pivoted to said plate, the oar-blade having its stem loosely mounted in said socket, the pin projecting from stem through said slot, the spring R, secured to said socket and adapted to lock said pin at either end of said slot, a button held by said plate, and the levers pivoted to said plate and adapted by their engagement with said 25 button and pin to feather the oar, as described.

3. The combination, in a feathering-oar, of 30 the plate, the socket pivoted to said plate, the oar-blade having its stem loosely mounted in said socket, the pin projecting from said stem through the slot, a button held by said plate, the levers pivoted to said plate and adapted 35 to engage with said button and pin, and the link joining said levers, for the purpose specified.

4. The combination, in a feathering-oar, of 40 the rigidly-joined plates, the gears pivoted between said plates, and having, respectively, a slotted and unslotted socket, the handle fixed in the unslotted socket, the oar-blade having its stem loosely mounted in said slotted socket, the pin projecting from said stem through said 45 slot, the spring secured to said slotted socket for locking said pin, the button pivoted to the upper of said plates and to said unslotted socket, and the levers pivoted to said upper plate and adapted to engage with said button 50 and pin, as set forth.

In testimony that I claim the foregoing invention I have hereunto set my hand and seal this 19th day of April, in the year 1886.
